(57) **CLAIM**

We claim the ornamental design for the rollable solar charger, as shown and described.

DESCRIPTION

FIG. 1 is a left perspective view of the rollable solar charger, showing our new ornamental design in a refracted position; FIG. 2 is a right perspective view of the rollable solar charger, showing our new ornamental design in a retracted position; FIG. 3 is a rear view of the rollable solar charger, showing our new ornamental design in a retracted position;

FIG. 4 is a bottom view of the rollable solar charger, showing our new ornamental design in a refracted position;

FIG. 5 is a front view of the rollable solar charger, showing our new ornamental design in a refracted position;

FIG. 6 is a left side view of the rollable solar charger, showing our new ornamental design in a retracted position;

FIG. 7 is a right side view of the rollable solar charger, showing our new ornamental design in a retracted position;

FIG. 8 is a left side view of the rollable solar charger, showing our new ornamental design in a partially extended position;

FIG. 9 is a right side view of the rollable solar charger, showing our new ornamental design in a partially extended position;

FIG. 10 is a left perspective view of the rollable solar charger, showing our new ornamental design in a partially extended position;

FIG. 11 is a right perspective view of the rollable solar charger, showing our new ornamental design in a partially extended position;

FIG. 12 is a front view of the rollable solar charger, showing our new ornamental design in a partially extended position; and,

FIG. 13 is a bottom view of the rollable solar charger, showing our new ornamental design in a partially extended position.

The ornamental design claimed includes both a housing and a roll-up solar cell array which extends from and retracts into the housing.
